FURNACE CONSTRUCTION

Louis H. Hosbein, Glencoe, Ill., assignor to M. H. Detrick Company, Chicago, Ill., a corporation of Delaware

Application April 22, 1939, Serial No. 269,400

1 Claim. (Cl. 110—1)

This invention relates in general to furnace wall construction, and more particularly to thin dividing walls of refractory material for use between separate and adjacent furnace units, such as oil cracking stills.

A principal object of the invention is the provision of such a thin dividing wall which includes vertically disposed, metallic tubes extending therethrough and spaced from each other as far apart as is consistent with maintaining the necessary stability of the wall.

Another important object of the invention is the provision of insulation around the tubes employed in such a wall to materially decrease the transfer of heat from the furnace to the tubes and to eliminate the usual black spots which would otherwise form in the refractory portions of the wall adjacent the tubes.

A further important object of the invention is the provision of such a wall which is completely leak proof, both transversely and longitudinally thereof.

Another object of the invention is the provision of such a wall for use between top-fired or downdraft furnace units, so that additional air for combustion purposes will be automatically supplied at the top thereof through said tubes.

Numerous other objects and advantages of the invention will be apparent as it is better understood from the following description, which, when taken in connection with the accompanying drawing, discloses a preferred embodiment thereof.

In the drawing,

Figure 1 is an elevational view, with parts 35 broken away and partly in section, of a furnace wall embodying the features of the instant invention;

Fig. 2 is a transverse, vertical section taken substantially on the line 2—2 of Fig. 1; and

Fig. 3 is a horizontal sectional view taken substantially on the line 3—3 of Fig. 2.

The wall shown in the drawing, and indicated generally by reference numeral 11, is a thin dividing wall interposed between adjacent furnace units, such as in a battery of oil cracking stills, in which the separate units are top-fired from a point above the I-beams 12 which extend transversely across the furnace units. The wall 11 comprises a plurality of longitudinally spaced, parallel tubes 13 having their axes in a common plane extending transversely of the furnace units between adjacent I-beams 12. The lower ends of the tubes 13 are cut away on opposite sides to provide shoulder portions 14 which

rest upon and are supported by a pair of I-beams 15 extending transversely across the furnace units parallel with the I-beams 12.

Adjacent its upper end, which extends between the I-beams 12, each of the tubes 13 is provided with a pair of upper and lower ring members 16 and 17 surrounding the tube and having diametrically opposed flange portions extending outwardly therefrom. The main portion 10 of each of the rings 16, 17 has a sufficiently small diameter to permit sliding of the rings upon the tube between the I-beams 12. The flange portions of the rings 16, 17 are of such length as to engage above and below, respectively, the lower inner flanges of the I-beams 12. Consequently, the rings 16, 17 are placed over the upper end of the tube 13, slid downwardly between the I-beams 12, and rotated through 90° to their position of Figs. 1 and 2. Bolts 18 extend through suitable apertures at opposite sides of the rings 16, 17 to clamp the same upon the lower flanges of the I-beams 12. In this position, the rings 16, 17 function as a temporary retaining guide means for holding the tube 13 in vertical alignment with the other tubes employed. Each of the tubes 13 is provided with an outer covering 19 of paper, and the tubes are made of an alloy that will effectively withstand temperatures up to 1800°.

After the several tubes 13 have been mounted in desired position, wherein they are retained by the guide rings 16, 17, refractory bricks or tiles 21 and 22 are laid upon the bottom I-beams 15 and surrounding the tubes to build up the wall 11. The bricks 21, 22 are laid in double rows extending transversely of the tube axes, with the bricks of adjacent rows disposed in staggered relationship relative to each other. As is seen in Fig. 3, each of the bricks 21 is cut away at 23 at one corner thereof to provide a vertically extending, curved recess having a greater radius than that of the pipe 13, so that a space is provided between the pipe and the brick. Four bricks 21 thus surround each pipe 13 in each row, with the cut-away portions 23 thereof forming an annular space between the pipe and the bricks.

The bricks 22 are similar to the bricks 21, except that they are not provided with the cut-away corner portions of the latter. The end surfaces of the bricks 21 and 22 are corrugated, as shown at 24 in Figs. 2 and 3, to provide vertically disposed, alternate recesses and ribs which interlock with the corrugated portions of the adjacent bricks. The joints between the bricks extending transversely of the wall 11 are consequently com-

pletely leakproof, and since the bricks in adjacent rows are in staggered relationship, there are no vertically disposed, straight line joints therebetween. Since the temperature at the top or upper portion of this type of downdraft furnace is greater than that obtaining elsewhere therein, the top portion of the wall 11 is preferably formed of a plurality of rows of bricks 25, 26 which are similar to the bricks 21, 22 in all respects with the exception that they are wider than the bricks 21, 22 to provide a thicker wall section in this higher temperature zone.

After all of the bricks 21, 22, 25 and 26 have been laid, a suitable fluid plastic material 27 is poured into the annular recesses surrounding the several pipes 13, from the top of the wall. The plastic material 27 will thus completely fill the annular pipe surrounding spaces formed by the cut-out portions 23 of the bricks to effectively insulate the pipes 13. Consequently, the transfer of heat from the refractories 21, 22, 25 and 26 to the pipes 13 will be materially reduced, and the black spots which would otherwise form on the refractories adjacent the pipes will be entirely eliminated. The plastic material 27 also eliminates vertical air seams in the wall 11, which, if present, would cause the downward sucking of hot gases through the pipes 13. This would result because the air or gases around the tubes would be cooler and would sink, thus sucking hot gases downwardly from the top of the furnace. With the elimination of this undesirable result by the plastic insulating material 27, the tubes 13 will function to supply additional air for combustion at the top of the furnace units, since the ends of the tubes are left open and the zone of highest temperature is at the top of the furnace.

The tubes 13 are disposed in spaced relationship to each other as far apart as is consistent with maintaining the necessary stability of the wall 11. After the plastic material 27 has been poured into the wall, the space between the upper portion of the tubes 13 and the usual suspended roof refractories 28 may be closed by means of blocks 29 mounted upon the upper

5 bricks 25, 26 and upper blocks 31 extending downwardly within such space and having side flange portions resting upon and supported by the refractories 28. The usual lower sloping walls 32 normally employed in such furnace units may then be built up in the manner shown in Fig. 2 to rest at their upper ends against the lateral surfaces of the dividing wall 11.

10 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

20 In a furnace, a partition comprising four parallel, horizontally extending I beams having horizontally disposed flanges and forming upper and lower pairs vertically spaced from one another, the members forming said pairs being horizontally opposed and spaced from one another, a plurality of parallel metal tubes extending vertically between said pairs of I beams, each of said tubes having a pair of opposed notches at the lower end thereof for seating on the top flanges of the lower pair of I beams and a collar slidably engaged on the upper end portion thereof, each of said collars having an opposed pair of horizontally disposed slots therein for sliding engagement over the adjacent lower flanges of said upper pair of I beams, a wall formed of a plurality of blocks of ceramic material vertically supported independently of said tubes by said lower pair of I beams, the blocks adjacent said tubes having arcuate openings therein of greater radius than the radius of said tubes whereby to form a vertically disposed annular channel between each of said tubes and the adjacent surfaces of said blocks, and a filler of plastic insulating material filling said channels.

30 LOUIS H. HOSBEIN.
